UNITED STATES PATENT OFFICE.

HARRY RALPH PILLINGER, OF EARLESTOWN, ENGLAND.

HUMAN POWER DRIVING MECHANISM FOR VEHICLES.

Application filed October 12, 1925, Serial No. 62,142, and in Great Britain October 20, 1924.

This invention has general reference to devices for propelling a vehicle by the weight and energy of the human body, and it consists essentially in the combination of parts and details of construction as herein-after set forth.

The method of propelling the vehicle is accomplished by utilizing the weight of the body on two levers, one called the foot lever, and the other called the saddle-lever.

In order that those skilled in the art to which this invention appertains, may understand how to make and use the same, I will describe its construction in detail, referring by letters to the accompanying drawings forming a part of this application, in which:

Fig. 1, is a side view of my present invention.

Fig. 2, is a top view of Fig. 1.

Fig. 3, is a back view of Fig. 1, and

Fig. 4, is a sectional elevation of the drum M.

The saddle lever A is a long lever, one end working freely on a pin B fixed to the framework near the front end of the vehicle. To the other end of this lever is attached the saddle or seat C. The person's weight in the saddle or seat is capable of forcing it down a distance of about a foot, whereby this movement draws out a series of powerful springs D having their respective ends connected to brackets D¹ and D². The bracket D¹ being supported by the frame member D³, and the bracket D² depending from the saddle lever A as shewn in Figs. 1 and 3.

Working in conjunction with the saddle lever is a lever for the feet. This said foot lever E works freely on pins F fixed to the framework at back end of vehicle, said foot lever E works below the saddle lever A, and extends inwards to the centre of the machine. To this end is fixed a footboard G in such a position, that a person sitting in the saddle or seat C will be able to place his feet comfortably on it. The saddle lever A and the foot lever E are connected by a chain H being secured thereto at H¹ and H² as shewn in Fig. 1, which runs over a roller J, this roller being suspended above the saddle lever. If the saddle lever A is forced down by the person's weight, it automatically raises the foot lever E. When the person raises himself from the saddle A and stands on the foot lever E, by means of the chain attachment H aforementioned, the weight

of the body helps to force the saddle lever A up again.

Underneath the aforesaid saddle lever A is a driving shaft K, having a drum L rotatably mounted, and encased in this said drum is a small ratchet wheel M being keyed tightly to the driving shaft K. Inside said drum L are small ratchet pawls N, which engage in the ratchet wheel when the drum L is moved in a forward direction as shewn in Fig. 4. The saddle lever A is connected to this said drum L by means of a chain O which latter winds round the drum L when the said saddle lever is forced down. Said chain O is wound round the drum L by means of another chain P to which is attached a tension spring Q, whereby it will be readily seen that when a person raises himself from the saddle A and stands on the foot lever E the weight of the person is again brought to bear on this drum L thereby operating the driving shaft K.

I claim:

1. A human power driving mechanism for vehicles wherein the motive force is obtained by the weight and energy of the human body applied to a saddle lever and foot lever, characterized in that the saddle lever is pivoted to the front of the vehicle, and the foot lever being connected to the rear of the vehicle, the levers being connected by a chain, and the drive being effected by pawl and ratchet mechanism on the rear axle and chains connecting the saddle lever and the pawl and ratchet mechanism.

2. A human power driving mechanism for vehicles wherein the motive force is obtained by the weight and energy of the human body applied to a saddle lever and foot lever, characterized in that the saddle lever is pivoted to the front of the vehicle, and the foot lever to the rear of the vehicle, the levers being connected by a chain running over a roller and the drive being effected by pawl and ratchet mechanism on the rear axle and chains connecting the saddle lever and the pawl and ratchet mechanism.

3. A human power driving mechanism for vehicles having a saddle lever and foot lever, characterized in that the saddle lever is pivoted to the front of the vehicle, and the foot lever to the rear of the vehicle, the levers connected by a chain running over a roller suspended above said saddle lever, a driving shaft having a drum rotatably mounted thereon with a ratchet wheel enclosed

2
therein keyed to said shaft, said drum provided with ratchet pawls engaging with said ratchet wheel when said drum is moved in a forward direction operating the driving shaft.

4. A human power driving mechanism for vehicles having a saddle lever and foot lever, characterized in that the saddle lever is pivoted to the front of the vehicle, and the 10 foot lever to the rear of the vehicle, the lever being connected by a chain running over a roller suspended above said saddle

lever, a driving shaft with a drum rotatably mounted thereon, a ratchet wheel keyed to said driving shaft engaging with ratchet 15 pawls carried by said drum, the latter connected to said saddle lever by means of a chain wound round said drum, by means of another chain attached to a tension spring operating the driving shaft.

20 In testimony whereof I have signed my name to this specification.

HARRY RALPH PILLINGER.
